232,207

STRAND OF BEADS FOR A CURTAIN ELEMENT OR THE LIKE

Irving Levine, 23555 Park Belmonte,
Calabasas Park, Calif. 91302

Filed Nov. 10, 1972, Ser. No. 305,605

Term of patent 14 years

Int. Cl. D6—10

U.S. Cl. D6—205

The drawing is a side elevation view of a strand of beads for a curtain element or the like illustrating the new design.

I claim:

The ornamental design for a strand of beads for a curtain element or the like, substantially as shown.

References Cited

Designing and Making Handwrought Jewelry, by Joseph S. Shoenfelt, © 1960, pp. 108 and 109.
Montgomery Ward's, Fall and Winter, © 1969, Balt., p. 778, item 73.

LOIS S. LANIER, Primary Examiner